UNITED STATES PATENT OFFICE.

JOSEPH P. OUERBACKER, OF LOUISVILLE, KENTUCKY, ASSIGNOR TO THE
O. K. STOVE AND RANGE COMPANY, OF SAME PLACE.

DESIGN FOR A FIRE-PLACE FRONT.

SPECIFICATION forming part of Design No. 21,121, dated October 20, 1891.

Application filed September 14, 1891. Serial No. 405,705. Term of patent 8½ years.

To all whom it may concern:

Be it known that I, JOSEPH P. OUERBACKER, a citizen of the United States, residing at the city of Louisville, county of Jefferson, and 5 State of Kentucky, have invented and produced a new and original Design for Grates, of which the following is a specification, reference being had to the annexed drawings, forming a part thereof.

Figure 1 is a front elevation of my new grate, and Fig. 2 is a side elevation of the face-plate thereof with the grate-basket removed.

The leading feature of my design consists in a raised ornamentation to be formed on the 15 surface of cast metal or other grates, said ornamentation including, among its other features, a hood H, projecting outwardly in an oblique direction above the fire-grate, said hood gradually retreating to the general plane 20 of the surface of the face-plate at a point below its outer lower corners through the molding A, as shown, and rising from said molding back and up in an oblique direction to a point on the face-plate near the top line there-

of I provide a raised and figured bead or border a up the two sides and across the top of the face-plate, while next within said bead is a plain panel or surface b, devoid of ornamentation. The hood or ledge H is provided along its lower edge with the ornamental line of 30 raised work c, as shown, while at a point slightly removed from the middle of the length of the hood there are two branches represented as rising from said line in graceful curves, and each of said branches is provided with 35 two stems filled with foliage, as shown.

What I claim is—

The design for a grate-front, substantially as herein shown and described.

In testimony whereof I have hereunto 40 signed my name, in the presence of two attesting witnesses, at Louisville, in the county of Jefferson, in the State of Kentucky, this 1st day of September, 1891.

JOSEPH P. OUERBACKER.
